COTTON PICKER DOFFER MEANS

Louis E. Nickla, Memphis, Tenn., assignor to International Harvester Company, a corporation of New Jersey

Application April 18, 1951, Serial No. 221,604

5 Claims. (Cl. 56—41)

1

This invention relates to cotton harvesters of the class shown and described in U. S. Patent 2,140,631 issued to E. A. Johnston on December 20, 1938, and more particularly to a novel mounting for the doffer means.

Present constructions based on this patent comprises a plurality of crop-gathering elements in the form of barbed spindles which move in a determined orbit such that the spindles follow a sequence of entering a cotton plant to gather the lint and then, laden with the crop, moving to a doffing station, whereat means are employed to remove or strip the cotton therefrom. This process is repetitive as explained in the patent.

The doffing means comprises a series of vertically spaced doffer assemblies carried on a driving shaft, each assembly including a disc with several doffing members or pads employed to sweep over a specified horizontal row of spindles. The pads are generally formed of rubber or the like and in use are gradually worn away so that periodic adjustment is required for proper functioning of the mechanism.

The adjustment in current use is manually operated and sets the doffer assemblies in one position which remains unchanged until a subsequent manual resetting. During each adjustment the operator is required to guess at the setting to provide for an average condition. In addition, in practice the operator is usually less discriminating and frequently sets the doffer means as low as possible so that the doffing elements are pressed into contact with the spindles. As a result, the spindles as well as the doffers are subjected to heavy intermittent stresses because of inadequate clearance therebetween. These conditions also accelerate wear. At times, due to a choke in the conveyor system, insufficient moisture, or improper adjustment, a spindle may become wrapped with a wad of cotton and foliage which fails to doff and is forced under the doffer discs. Inasmuch as current mechanisms do not provide any relief for such conditions the parts are either bent out of shape or frequently broken.

A general object of the invention is to provide a doffer mechanism of simple and effective design and which will alleviate the conditions discussed.

A more specific object is to provide a novel doffer mechanism incorporating a resilient means cooperating with the adjusting means to provide a yielding construction which will accommodate uneven bunching of plant matter on the spindles.

The invention contemplates a doffer mechanism comprising a shaft with doffer assemblies thereon, the shaft being adjustable to position

2

the assemblies with respect to the spindles and the shaft being associated with resilient means arranged to bias the mechanism to its adjusted position, the doffer mechanism being movable against the resistance of the resilient means to clear heavy bunching of crop and the like on the spindles.

A different object of the invention is to arrange the resilient means so that it maintains the parts of the doffer adjusting mechanism in tight assembly with each other and also serves as an anti-rattling device. A spring provides a resilient adjustment to protect the parts contacting spindles.

A further object is to arrange the resilient means in a manner that it frictionally interlocks the adjusting assembly with other members of the doffer mechanism to maintain the adjusting mechanism in selected adjusted position.

These and other objects of the invention will become more apparent from the specification and the drawings wherein:

Figure 1 is a fragmentary side elevational view of a doffing mechanism incorporating the invention, portions of the mechanism being shown in vertical section, the view also showing the relationship of the doffing mechanism with the picking spindles of the picking mechanism fragmentarily shown, and

Figure 2 is a fragmentary top plan view thereof. Describing the invention in detail, the doffer mechanism generally indicated 2 is associated with a picking mechanism generally indicated 4 which is herein illustrated as comprising a bar 6 with a plurality of spindles 8, 8 thereon. This spindle carrier 6 is but one of several of such members embodied in a cotton picking unit as that shown in the above mentioned Patent No. 2,140,631. The operation of the picker unit 4 is as explained in the patent and it will suffice to say for the present purpose that each spindle 8 gathers a crop thereon and moves to the doffer mechanism 2.

The doffer mechanism or doffer element means 2 comprises a substantially vertical driving shaft 10 carrying a plurality of doffer disc assemblies 12, 12 rotatable therewith, each doffer disc 12 being associated with a specified horizontal row of spindles 8. It will be understood that the assemblies 12 are arranged to sweep tangentially across the row of spindles associated therewith. The discs may be secured to the shaft 10 in any convenient manner as by splines such as shown in the before mentioned patent, or they may be clamped by means of nut 32, with no other driving means except friction.

The shaft 10 may be supported from a housing structure or support 14 enclosing the entire mechanism. This housing may be as shown in the patent and may comprise a cast upper head 16 to which the other portions of the housing are connected, the latter of which may comprise a bottom closure plate 18 to which may be secured in any convenient manner as by bolt and nut assemblies 20, 20 a bearing cup 22 which may have an upwardly opening bearing receiving cavity 24 within which may be disposed the lower end of the shaft 10 which is preferably of reduced cross-section, the shaft extending into an inner race 26 of a bearing generally indicated 28, the outer race 30 of the bearing having a slidably complementary fit within the opening 24. The bearing 28 may be secured to the shaft by a nut 32 threaded on the lower end of the shaft and bearing against the lower edge of the inner race 26, the upper edge of which seats against the lower side of a washer 34, said washer seating at its upper side against an inturned flange 36 of a dust cap 38, the flange bearing against the sleeve 40 of the lowermost doffer assembly 12, and the dust cap telescoping over the upper extent of the cup member 22.

The upper end of the shaft is ensleeved by a driving gear 42 which has a splined connection 44 with the shaft and is slidably axially thereon. The driving sprocket member 42 has an axially extending collar 46 at its lower end with a radial seating face 48 at the lower edge thereof providing a seat for the upper end of a compression spring 50 which is sleeved on the shaft and at its lower end seats as at 52 against the top side of an abutment member in the form of a cotter key 54 which extends transaxially through a complementary opening in the shaft.

The sprocket member 42 has an upwardly extending sleeve 56 which has a beveled upper edge 58 which seats as at 60 against the bottom edge of an inner race 62 of a bearing generally indicated 64, the race 62 encircling a reduced upper portion 63 of the shaft 10 and having a slidably fit therewith, whereby the shaft and the bearing are movable axially relative to each other. The race 62 is associated with a plurality of ball bearings 66 which are located between it and the outer race 70 of the bearing 64. The race 70 is nested within a bearing cup 12 and on its bottom side seats against the top side as at 72 of an inturned flange 74 at the bottom edge of the cup 72. A seal 76 is provided between the inner and outer races 66 and 70 of the bearing 64, and it will be seen that the beveled face 58 of the sleeve 66 of the sprocket 42 provides adequate clearance with respect to the seal 76 and the inner periphery of the flange 74.

The upper edge of the inner race 62 of the bearing 64 affords a seat as at 60 for the lower edge of a spacer sleeve 82 sleeved on the upper portion 63 of the shaft 10 above the bearing 64, the upper edge of sleeve 82 constituting stop means affording an abutment surface as at 84 for the bottom side of a split nut or adjusting means 86 which is threaded on the upper end of the reduced portion 63 of the shaft 10.

The bearing 64 is locked to the cup 72 by means of a radially outwardly expanding split ring 88 which seats against the top side of the outer race 70 of the bearing 64 and snaps into a groove 90 within the inner periphery of the cup 72.

The cup 72 is nested within a complementary opening 92 in the top side of the housing head 16 and the upper end of the shaft and the assembly within the cup 72 may be covered by a cap 94.

which may be secured to the head 16 together with cup 72 by a plurality of bolts 96. The cups 72 and 22 together with the related bearings and housing 14 may constitute a rotatable mounting for the doffer assembly and accommodating axial movement thereof.

In operation the shaft 10 together with the doffer disc assemblies 12, 12 is rotated by means of a driving member such as a chain around the sprocket 42. Simultaneously the spindles 8, 8 laden with cotton move under the doffer members 12, 12. In the event that any spindle picks an unusually large wad of cotton or any other plant matter thereon which does not doff and attempts to pass under its associated doffer assembly 12, the doffer mechanism 2 will rise against the resistance of the spring 50 compressing the same. Immediately thereafter the doffer mechanism will be urged downwardly and normal operation proceeds. The spindle with the large amount of plant matter thereon will either have been cleared or the plant matter will dislodge in a short while.

It will be seen that in addition to the spring 50 providing a yieldable action for the doffer mechanism 2 it also holds the gear 42 in proper position with respect to the drive chain trained thereon and it also holds the gear 42 tightly against the inner race 62 of the upper bearing 64. Additionally the spring 50 biases the doffer mechanism downwardly to its adjusted position and also frictionally couples or engages the sleeve 82 with the race 62 and urges the nut 86 into tight frictional engagement with the sleeve 82. This eliminates rattling and also frictionally maintains the parts in adjusted position in the event that the locking bolt 98 extending through the split ends of the nut 86 is negligently not tightened by the mechanic after each adjustment. It will be understood that the nut 86 and the sleeve 82 may be constructed as one piece.

It will be noted that the arrangement described effects a further novel function in that with new doffer discs and new spindles, the doffer assembly, which is adjusted to uppermost position, loads the spring 50 under maximum predetermined compression so that in such position of the doffers a substantial force is required to lift the doffer assembly upwardly. Inasmuch as new spindles are more difficult to doff than worn spindles, this effect is especially desirable, because the increased pressure of the doffers against the crop insures adequate doffing of the new spindles. As the doffer discs and the bars wear, the doffers are lowered, which reduces the loading of the spring 50 with commensurate reduction in the rate of wear of the co-operating parts while at the same time effecting satisfactory doffing without unnecessarily highly stressing the parts.

What is claimed is:

1. In a doffer unit of the class described, a support, a shaft rotatably mounted thereon and movable endwise, abutment means on the shaft spaced axially of said support, doffer means connected to the shaft for movement therewith, and spring means reacting between said abutment means and said support and biasing said unit in a direction positioning the doffer means in co-operating relationship with associated picker means, said unit being automatically movable away from said picker means against the resistance of said spring means to relieve congestion therebetween.
2. In a doffer mechanism for a cotton harvester of the spindle type, a support, a rotatable doffer

assembly movably carried thereby and movable axially to a position in cooperative relationship with the spindles, stop means on the support cooperatively positioned with respect to said assembly, adjusting means connected to the assembly and in abutment with said stop means for adjusting the position of the assembly with respect to the spindles, and resilient means reactively disposed between said support and said assembly and biasing said assembly to the adjusted position thereof and frictionally engaging said adjusting means with said stop means to resist unadjusting movements of said adjusting means.

3. In a cotton harvester of the type having a substantially horizontal row of rotating spindles, a doffer unit comprising a substantially vertical shaft, a doffer element connected to the shaft and arranged to sweep over the row of spindles, a support, a rotatable slidable connection between the lower end of the shaft and the support accommodating endwise movement of the shaft, a driving gear sleeved over the shaft adjacent to the upper end thereof and having splined connection with the shaft accommodating axial movement therebetween, a bearing carried by the support and sleeved over the shaft above the gear and seated on its bottom side thereagainst, said bearing and shaft being axially slidable relative to each other, abutment means on the shaft spaced beneath the gear, resilient means compressed between the gear and the said abutment means urging said shaft downwardly, and adjusting means acting between the upper end of the shaft and in seated engagement with the top side of the bear-

ing against the resistance of said resilient means.

4. In a doffing unit for a cotton harvester of the rotating spindle type, a substantially vertical shaft, a support, a bearing thereon slidably receiving the shaft therethrough, an adjusting nut assembly threaded on the upper end of the shaft and seated upon one side of said bearing, abutment means on the shaft disposed in opposing relationship to the opposite side of said bearing and resilient means reactively stressed between said abutment means on the shaft and said opposite side of the bearing to hold the nut assembly and bearing in tight axial engagement with each other.

5. In a cotton picker, a doffing unit comprising a substantially vertical shaft, a rotatable support slidably ensleeved about the shaft, an adjusting assembly in threaded engagement with the shaft and abutting one side of the support, a driving element connected to rotate the shaft and slidable axially thereon, and having an axial extension at one side in engagement with the opposite side of the support, and a spring sleeved over the shaft and compressed between the opposite side of the gear and an abutment surface carried by the shaft.
